Inventor,
Daniel H. Young, by
G. Kennedy,
Attorney.

UNITED STATES PATENT OFFICE.

DANIEL H. YOUNG, OF MANCHESTER, IOWA.

WATER-BAFFLING MEANS FOR BOILER-SPOUTS.

1,333,052.

Specification of Letters Patent.

Patented Mar. 9, 1920.

Application filed May 22, 1919. Serial No. 298,988.

To all whom it may concern:

Be it known that I, DANIEL H. YOUNG, a citizen of the United States of America, and a resident of Manchester, Delaware county, 5 Iowa, have invented certain new and useful Improvements in Water-Baffling Means for Boiler-Spouts, of which the following is a specification.

My invention relates to improvements in 10 water baffling-means for boiler spouts, and the object of my improvement is to position in the steam delivery spout of the boiler of a humidifier or other vessel, means for obstructing and returning water passing into 15 the spout because of intense ebullition of the contents of the boiler, while permitting free delivery of vapor generated within the boiler.

This object I have accomplished by the 20 means which are hereinafter described and claimed, and which are illustrated in the accompanying drawings, in which Figure 1 is an elevation of a boiler provided with a laterally directed spout containing my improved water-baffling means, said spout and a portion of the boiler being in longitudinal section. Fig. 2 is an end elevation of the delivery end of said spout, and Fig. 3 is a plan of the water baffling-means for said 25 spout.

Similar numerals of reference denote corresponding parts throughout the several views.

The numeral 7 denotes a boiler having a 30 cover 8 and a lateral spout 6. The spout is inclined very slightly downwardly toward the boiler to permit return flow of water while allowing a lateral flow of steam. Intense ebullition of the boiling water in said 35 boiler will occasionally cause the ejaculation of small quantities of the water from said spout, and it is to prevent this that I provide my baffling-means consisting of a single longitudinally troughed plate 1 whose forward end is bent downwardly and secured in 40 the delivery end of said spout as shown at 2, to close the lower part of the delivery opening, the plate extending thence nearly through the spout toward the boiler and inclined at a slight angle to the latter. The 45 trough in said plate begins near the part 2

and is continuous to the rear end of the plate where it is slightly bent down at 5.

The numeral 4 denotes a plurality of triangular tongues which, however, may be of 55 any other shape, partially cut out of the troughed part of plate 1 in longitudinal alignment, bent upwardly at an angle to the plate with their apices directed toward the boiler, the openings at their bases serving for drainage. The numeral 3 denotes a single semi-circular tongue partially cut from the forward part of the trough of said plate and bent downwardly outwardly to furnish another drainage opening. 60

In the event that boiling water is forced into said spout in relatively small quantities, the portion which passes under the plate 1 is baffled by the part 2 and flows back to the boiler. Such portion as may move through 70 the upper part of the spout will be baffled by the tongues 4, thence drained through the openings at the bases of the tongues or returning along the trough of the plate to be returned to the boiler by the inclined tip 5. 75 Any particles of water which may have advanced forwardly beyond the tongues 4 will drain through the opening in the plate at the base of the depending tongue 3 and return through the lower part of the spout. 80

As the steam tends to move through the spout in its upper portion, its delivery therethrough is not perceptibly impeded. My improved baffling means may be considerably varied in form and position without departing from the principle of the invention. 85

Having described my invention, what I claim as new, and desire to secure by Letters Patent, is:

1. Water baffling-means for spouts, consisting of a plate fixed within a spout to close the lower part of its delivery-opening, thence directed inwardly at a slight angle to the horizontal, and provided with upwardly-directed baffling-tongues. 90

2. Water baffling-means for spouts, consisting of a longitudinally troughed plate supported in a spout, with one end closing the lower part only of the spout. 95

3. Water baffling-means for spouts, consisting of a longitudinally troughed plate supported in a spout longitudinally in 100

spaced relation, and having upwardly directed baffling-projections, and openings positioned at the bases of the projections.

4. Water baffling-means for spouts, consisting of a plate supported in a spout in spaced relation longitudinally and having an end bent downwardly to close the lower part of the delivery-opening of the spout,

said plate having baffling-projections and drainage openings positioned therealong to 10 permit passage of vapor while baffling and returning a liquid.

Signed at Waterloo, Iowa, this 5th day of May, 1919.

DANIEL H. YOUNG.
